(No Model.)

A. HANSEN.

BRAKE LOCK.

No. 381,010.

Patented Apr. 10, 1888.

UNITED STATES PATENT OFFICE.

ANDREW HANSEN, OF RACINE, WISCONSIN, ASSIGNOR OF ONE-THIRD TO
CHARLES P. JORGENSEN, OF SAME PLACE.

BRAKE-LOCK.

SPECIFICATION forming part of Letters Patent No. 381,010, dated April 10, 1888.

Application filed December 27, 1887. Serial No. 259,032. (No model.)

To all whom it may concern:

Be it known that I, ANDREW HANSEN, a citizen of the United States, and a resident of Racine, in the county of Racine and State of Wisconsin, have invented certain new and useful Improvements in Brake-Locks; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of as much of the 15 brake mechanism of a vehicle as is necessary to illustrate the operation of my improved brake-lock; and Fig. 2 is a similar view showing the lock disengaged and the lever free to be tilted, Fig. 1 showing the lock engaging the 20 rail.

The same numerals of reference indicate the same or corresponding parts in all the figures.

My invention has relation to brake-locks; and it consists in the improved construction 25 and combination of parts of such a lock in which the brake-lever is held in position by a pivoted and weighted cam clamping a segmental rail, as hereinafter more fully described and claimed.

30 In the accompanying drawings, the numeral 1 indicates the side of the vehicle upon which the brake-lever 2 is pivoted at its lower end, having the brake-rod 3 suitably pivoted to it. The lever is provided with a downwardly- 35 projecting lip, 4, which straddles a segmental rail or bar, 5, which is suitably supported by means of posts 6 from the side of the vehicle, the lever rocking between the segmental bar and the side of the vehicle. The segmental 40 bar has its center in the fulcrum of the brake-lever.

An angularly-bent arm or cam, 7, is pivoted with its lower end upon the outer side of the 45 brake-lever, and has its cam-face 8 in contact with the inner edge of the segmental rail or bar, and the forwardly-projecting portion of the cam-arm is provided with a weight, 9, and has the rod 10 pivoted to it, which is pivoted to the rectangularly-bent lock-handle 11 at its

upper end, the said handle being pivoted at 50 the upper end of the brake-lever.

The cam-arm plays between the lever and the lower end of the lip, and it will be seen that the weight of the forwardly-projecting arm will tilt the cam-arm forward, bringing 55 it in contact with the segmental rail or bar, against the lower concave edge of which it will bear and bite, so that any rearward pull or tilt upon the brake-lever will merely serve to lock the cam against the bar, causing it to 60 clamp the same more firmly.

When it is desired to release the brake-lever, the bent handle at the upper end of the lever is tilted inward toward the lever, raising the forward portion of the cam-arm and 65 tilting the said arm down and away from contact with the rail or bar, so that the lever may be tilted back.

The lever may at all times be tilted forward, as the cam-arm tilts freely rearward, 70 but cannot be tilted forward without bearing harder with its cam-face against the edge of the segmental rail or bar.

The cam-face and the lower edge of the segmental bar or rail are preferably formed with 75 serrations, as shown in the drawings, for the purpose of effecting a more perfect frictional resistance; but these serrations may be dispensed with, if desired.

It will be seen that by using this lock the 80 construction of the brake and lock will be considerably simplified over the construction of the usual brake-lever and lock with its sliding or tilting bolt engaging a cogged rack, and in this improved lock the holding power of 85 the lock will not be impaired or affected by any collection of mud or dirt upon the rail or bar, while a cogged rack or rail will be obstructed to the free engagement of the bolt by accumulations of mud or dirt, preventing the 90 bolt from entering the notches between the cogs.

In this construction of lock the cam will 95 clean all accumulated mud or dirt off from the bar, and then bite as firmly or possibly firmer than upon a clean bar, there being no bolt to engage spaces between cogs.

Having thus described my invention, I claim

and desire to secure by Letters Patent of the United States—

In a brake-lock, the combination of a lever having the brake-rod pivoted to it, a segmental rail or bar concentric with the fulcrum of the lever and having its lower concave edge serrated, a cam pivoted upon the lever at its lower end and bearing with its serrated cam-face against the lower edge of the segmental bar or rail, and having a forwardly-extending

weighted arm, and a rod pivoted to the said arm at its lower end and having a tilting handle at its upper end, as shown and described.

In testimony that I claim the foregoing as my own I have hereunto affixed my signature in presence of two witnesses.

ANDREW HANSEN.

Witnesses:

A. CHR. PETERSON,
J. W. JOHNSON.
